FIG. 2.

FIG. 1.

INVENTOR

Carl R. Waller

BY

Frank J. Busen

ATTORNEY.

WITNESS:

W. R. Kitchell

UNITED STATES PATENT OFFICE.

CARL R. WALLER, OF TRENTON, NEW JERSEY, ASSIGNOR TO DE LAVAL STEAM TURBINE COMPANY, OF TRENTON, NEW JERSEY, A CORPORATION OF NEW JERSEY.

STEAM-TURBINE.

1,338,409.

Specification of Letters Patent. Patented Apr. 27, 1920.

Application filed October 1, 1919. Serial No. 327,651.

To all whom it may concern:

Be it known that I, CARL R. WALLER, a citizen of the United States, residing at Trenton, county of Mercer, and State of 5 New Jersey, have invented a new and useful Improvement in Steam-Turbines, of which the following is a full, clear, and exact description, reference being had to the accompanying drawings, which form a 10 part of this specification.

In designing a steam turbine for marine propulsion, provision must be made to operate the turbine in either direction so as to facilitate its operation ahead and 15 astern. To this end, it is a common practice to use two sets of turbine wheels and admit steam to these wheels independently. It is also a practice to make the steam admission at the two extreme ends of the turbine 20 casing, allowing two sets of wheels to utilize a common exhaust. This design is undoubtedly preferable where a single turbine is utilized, but if a compound turbine is used, and if reversing elements must be 25 provided in both the high and low pressure turbine, provisions are made to keep the exhaust of the high pressure ahead turbine separated from the exhaust of the high pressure astern turbine. The object 30 of my invention is to improve the construction of this type of turbine. The nature of the improvement will be clear from the subjoined description of the preferred embodiment of the invention shown in the 35 drawings, in which—

Figure 1 is a sectional view of a portion of a high pressure steam turbine embodying my invention.

Fig. 2 is a cross-section taken on the line 40 2—2 of Fig. 1.

The turbine case is made in three semi-cylindrical sections,—two end sections *a* and *b* and an interposed connecting section *c*. The section *c* has an inwardly projecting steam chest *d* for (say) the reversing 45 turbine.

The turbine cover is made in three similar semi-cylindrical sections,—two end sections *e* and *f* and an interposed connecting section *g*. The section *g* has an inwardly projecting semi-annular steam chest *h* for (say) the ahead turbine.

By making section *c* *d* separate from sections *a* and *b*, they can be made of different 50 material from sections *a* and *b*; that is, of

metal more suitable for high pressure steam. For the same reason, section *g* *h* is made separate from sections *e* and *f*.

In assembling, the turbine section *c* *d* is securely bolted to sections *a* and *b*, these 60 three sections being subsequently handled together and forming the case as distinguished from the cover. Section *g* *h* is similarly bolted to sections *e* and *f*, these 65 three sections forming the cover, which is also handled as a unit. The cover is placed upon the case in such position that the steam chests *d* and *h* form diametrically opposite walls dividing the turbine into two 70 chambers; one chamber containing the ahead turbine wheels, the first of which is shown at *i*, and the other chamber containing the astern turbine wheels, the first of which is shown at *j*.

When the turbine is running ahead, pressure in the chamber in which wheel *i* revolves will be higher than the pressure in the chamber in which wheel *j* revolves. Due to this difference in pressure, steam tends to leak along the shaft *k* from the higher 80 pressure to the lower pressure side. To prevent this, stuffing boxes *m*, *m* are provided. A bleed-off connection *n* is provided from the chamber that is formed between the stuffing boxes. 85

o is a maneuvering valve having one steam inlet and two steam outlets, the two steam outlets being connected respectively to the ahead chamber *h* and the astern chamber *d*, the valve being operable to admit steam to either chamber. 90

I am aware that it is old to provide a partition dividing a turbine into an ahead portion and an astern portion with nozzle boxes or steam chests communicating with 95 the respective chambers. In such constructions the steam chests are either arranged in different planes perpendicular to the turbine shaft; or the partition itself comprises two segmental sections located in different 100 planes perpendicular to the turbine shaft so that the two chambers overlap; or each steam delivery is formed in a semi-annular ring chest secured to the single casing or cover common to the ahead and astern compartments, which are separated from each other by a dummy piston mounted on the shaft and semi-annular partitions within the ring section. In my construction, the steam chests are not in the respective cham- 105 110

bers of the turbine on opposite sides of a partition, or in semi-rings secured to a single-piece casing or cover, but themselves form the dividing wall between the two 5 chambers of the turbine.

This arrangement is made feasible by making one steam chest an integral part of the central portion of the cover and the other 10 steam chest an integral part of the central portion of the case; these central sections being made separate from, and set in between, and secured to, the end sections of the complete turbine casing.

Having now fully described my invention, 15 what I claim and desire to protect by Letters Patent is:

1. A steam turbine comprising a case and a cover, each of said elements comprising semi-cylindrical secured-together sections, 20 namely: a central section and end sections; semi-annular steam chests formed integral with the central sections of the case and cover respectively and abutting one against the other to form two alining halves of a 25 wall dividing the turbine into separate wheel chambers.

2. A steam turbine comprising a case and cover and an intermediate wall dividing the 30 turbine into an ahead chamber and an astern chamber, said wall being hollowed out to form two steam chests communicating with the respective chambers, the case

and cover each comprising a semi-cylindrical section integral with said division wall and separate semi-cylindrical sections secured to 35 opposite ends of the first section.

3. A steam turbine comprising a shaft, spaced-apart stuffing boxes surrounding the shaft, and two division wall sections arranged in the same plane perpendicular to 40 the axis, each of said sections being hollow to provide a steam chest and also provided with an integral external semi-cylindrical flange, the flanges of said sections forming together the central part of the turbine 45 casing, and end sections secured to opposite ends of the central sections and forming with the central sections the cylindrical casing of the turbine, there being a bleed-off connection from the chamber formed between the stuffing boxes.

4. A steam turbine comprising two cylindrical casings forming compartments for the ahead and astern turbines, a centrally disposed shaft for the turbines, and a common internal head for said two compartments, to either side of which one of said casings is adapted to be bolted, there being two cored steam passages in said head on opposite sides of said shaft.

In testimony of which invention, I have hereunto set my hand, at Trenton, N. J., on this 29th day of September, 1919.

CARL R. WALLER.
